PAGE 2

FIG. 1 is a top plan view of a combined kaleidoscope and pencil case embodying my new design;

FIG. 2 is a top plan view thereof as it appears with the cover in open position;

FIG. 3 is a front elevational view of the design as shown in FIG. 1;

FIG. 4 is a rear elevational view thereof;

FIG. 5 is an end elevational view thereof as seen from the left of FIG. 4;

FIG. 6 is an end elevational view as seen from the right of FIG. 4; and

FIG. 7 is an end elevational view thereof looking in the direction of the arrows 7-7 on FIG. 2.

The essential features of my design reside in the portions shown in solid lines on the drawings.

I claim:

The ornamental design for a combined kaleidoscope and pencil case, substantially as shown and described.
